155,534

DESIGN FOR AN ADJUSTABLE FLATIRON STAND

Harry Noordhof, Grand Haven, Mich.

Application May 3, 1948, Serial No. 146,133

Term of patent 7 years

(Cl. D49—6)

To all whom it may concern:

Be it known that I, Harry Noordhof, a citizen of the United States, residing at Grand Haven, in the county of Ottawa and State of Michigan, have invented a new, original, and ornamental Design for an Adjustable Flatiron Stand of which the following is a specification, reference being had to the accompanying drawing, forming part thereof.

Fig. 1 is a perspective view of an adjustable flatiron stand, showing my new design,

Fig. 2 is a plan view of the same,

Fig. 3 is a side view of the same,

Fig. 4 is an end view of the same, and

Fig. 5 is an opposite end view of the same.

I claim:

The ornamental design for an adjustable flatiron stand, substantially as shown.

HARRY NOORDHOF.
